BOTTLE CLOSURE

Andrew Berger, Omaha, Nebr.

Application October 8, 1934, Serial No. 747,395

3 Claims. (Cl. 215—21)

This invention relates to bottle closures and more particularly to closures which will protect the producer or manufacturer of the contents.

It is well known that bottles containing chemicals, beverages, perfumery and drugs, used commercially, and which bear labels, symbols and trade-marks of manufacturers to designate origin and excellence in quality of the product, are often refilled with cheap and inferior ingredients and sold, these imitations operating to deceive the public and injuring the business of the original producer.

The object of the invention therefore, is to provide a bottle, jug or other receptacle which will permit removal of the contents but will prevent refilling and will prevent use of the bottle commercially, after the contents have been removed.

It is an object to provide a bottle closure which may be manufactured practically and at a limited cost, will be convenient in use, and will furnish absolute protection to a producer of chemicals, beverages or other liquid preparations, so that his bottles or other containers will not be refilled with spurious ingredients and sold commercially.

With the foregoing objects in view the invention consists of the new and useful features of construction, combination and arrangement of parts calculated to attain said objects, and as described herein and claimed, and as illustrated in the drawing, it being understood that changes may be made in size, proportions and minor details, said changes being within the scope of the invention as claimed.

In the drawing, Fig. 1 is a view of the device in longitudinal section, and Fig. 2 is a side view of a cork.

Fig. 3 is a transverse section through the neck of a bottle and cork on line 3—3 of Fig. 1, and Fig. 4 is a plan view of the bottom of the cork.

Referring now to the drawing for a more particular description, the invention is shown and described in connection with the rectilinear neck 5 of a bottle preferably constructed of glass or other frangible material, and in order that the objects may be attained as first mentioned I provide a rectilinear cork 6 preferably having a diameter corresponding to the bore of the neck 5, said cork having a chamber 7 adapted to contain a ball-valve 8 adapted to engage the valve-seat 9, other parts of the cork consisting of an inclined passageway 10 leading from the chamber 7 to a spillway 11 near the upper end of the cork, an annular stop-member or ridge or flange 12 being provided for the periphery of the cork near its upper end and having a flat base adapted

to have a seat on a flat ledge 13 which is formed in the upper part of the neck.

Numerals 14 indicates a screw-cap which may be mounted on the top of the cork, threads 15 (Fig. 2) being shown for this mounting.

Numerals 16 indicates a plurality of ridges which are provided for the wall of the chamber 7. They are disposed longitudinally of the neck and extend from the partition 17 toward the valve seat, and at 18 is indicated a projection or stop-member 10 which extends downwardly from the partition 17 into the chamber 7 centrally thereof, and at 19 is indicated a pocket which is disposed in line with the passageway 10 in the wall of the cork.

The parts thus described may be used as a bottle closure to prevent refilling of the bottle, and in operation, after the bottle has been filled the cork is inserted and the screw-cap is applied to the top of the cork.

After removing the screw-cap the liquid may be poured or emptied in the usual manner. When the bottle is moved to inclined position the valve will move from its seat, the liquid moving through the chamber 7, the passageway 10 and spillway 11. The ball-valve 8 may move on the ridges 16 and 25 may engage the stop-member 18 which will prevent the ball-valve from obstructing the lower end of the passageway 10, and when the ball-valve slides or rolls on the ridges 16 it is obvious that the grooves between the ridges will permit a movement of liquid from the valve-seat to the passageway 10, said valve being no material obstruction, and permitting said movement of the liquid without causing the objectionable "gurgling" noise sometimes caused by too closely confined liquids while moving outwardly from a bottle.

The ball-valve may be constructed of any suitable material and on account of gravity will normally remain on its seat. The cork is preferably constructed of galvanized rubber, and since it has a quality of limited elasticity, the ball-valve may be pressed upwardly into the chamber 7 to its normal position without injury to the valve-seat.

Since the valve normally remains on its seat refilling will be prevented, and an attempt to dislodge the valve from its seat by inserting some kind of tool, such as a wire downwardly through the passageway 10 will be prevented since the pocket 19 is intended, in such instances, to receive the end of such tool and prevent a further movement thereof toward said valve.

As an additional feature of protection and to prevent a second use of the bottle commercially

after the contents have been removed, parts are used for sealing the neck in such a manner that the screw-cap 14 cannot be removed until the bottle has been disfigured and changed in appearance in a degree sufficient to prevent deception.

This additional protection consists simply of a cement sealing-member 29 having the form of a cap adapted to fill an annular recess 21 provided by an annular curved extension 22 of the neck of the bottle at the upper end thereof, said annular recess being of such form that the cement cannot be removed or detached without breakage of the extension 22. Said extension 15 is provided with a weakline 23 disposed in a plane approximately in line and adjacent to the flat surface of the ledge 13, and by use of a suitable tool, such as a small hammer, the extension 21 together with the cap 29 may be readily removed, the result being that the appearance of the bottle will be changed, and fraud would be disclosed if an attempt was made to use the bottle a second time.

The cement is used when in a plastic condition but soon becomes hard, and when the glass flange or extension is separated from the neck 5 at said weakline 23 the screw-cap 14 will be accessible for removal.

Numeral 24 indicates the material which may bear the label of the manufacturer of the contents. This label is generally printed on a flexible strip, such as tinfoil, and it covers a part of the neck and the extension 22 of said neck, and when the glass extension is removed the label will be torn and changed in appearance, and if revenue stamps are attached to the cement cap they will become cancelled or torn in like manner.

The cork together with its annual ridge or flange 12 are secured stationary in the neck of the bottle preferably by use of cement. The aperture at the lower end of the hollow cork is of flaring form as indicated at x, its outwardly divergent wall extending uniformly from the

valve seat to the bottom of the cork at the outer surface thereof, so that the entire contents of the receptacle may be emptied, and that vibration of the liquid and resulting "gurgling" sounds may be avoided.

I claim as my invention:—

1. In a closure for a bottle having a rectilinear neck provided with a flat annular ledge, a curved terminal wall forming an annular recess outwardly of and above said ledge and provided with a weakline, a rectilinear stopper snugly fitting in said neck and having a valve-controlled passageway extending therethrough, an annular flange having a flat base for a seating on said ledge and having a threaded part outwardly of said flange, a cap engaging the threaded part of the stopper, and a sealing element in said recess engaging said flange and covering said cap.

2. In a closure for a bottle having a neck provided with a flat annular ledge, a curved terminal wall forming an annular recess outwardly of and above the ledge and provided with an annular weakline disposed in a plane approximately in line with the flat surface of said ledge, a stopper fitting snugly in said neck and having a valve-controlled passageway extending therethrough, an annular flange having a flat base for engaging said ledge, a screw-cap mounted on said stopper, and a sealing element in said recess engaging said flange and covering said screw-cap.

3. In a closure for a receptacle having a rectilinear tubular neck provided with a flat ledge and a curved extension terminating beyond said ledge providing an annular recess, a rectilinear stopper having a valve-controlled passageway and provided between its ends with an annular flange having a flat base, said stopper being disposed within the neck with its flange engaging the ledge thereof, a cap covering the passageway of said stopper, and a sealing-element in said recess engaging said flange and covering said cap.

ANDREW BERGER.
